UNITED STATES PATENT OFFICE.

CHARLES SALATHE, OF NEW YORK, N. Y., ASSIGNOR TO THE ADHESIVE GIMP COMPANY, (LIMITED,) OF SAME PLACE.

DESIGN FOR GIMP.

SPECIFICATION forming part of Design No. 19,585, dated January 14, 1890.

Application filed November 25, 1889. Serial No. 331,554. Term of patent 3½ years.

To all whom it may concern:

Be it known that I, CHARLES SALATHE, of the city, county, and State of New York, have invented and produced a new and original 5 Design for Gimp, of which the following is a specification, reference being had to the accompanying drawing, forming part thereof.

The said drawing illustrates a face view of a piece of gimp showing my design.

10 The said design consists of the longitudinal cords $a a'$, dividing the gimp into three equal parts transversely, bars a^2 , crossing the cords $a a'$, the longitudinal slanting lays or bands $a^3 a^4$ between the said cords $a a'$ and 15 the edges of the gimp, and the right-angular

lays or bands a^5 in the central part of the same.

What I claim is—

The design for gimp, consisting of the longitudinal cords $a a'$, dividing the gimp into 20 three equal parts transversely, bars a^2 , crossing the cords $a a'$, the slanting lays or bands $a^3 a^4$ between the said cords $a a'$ and the edges of the gimp, and the right-angular lays or bands a^5 in the central part of the same, 25 substantially as shown.

CHARLES SALATHE.
